A. T. REID

TOILET CASE

Filed Oct. 31, 1922

UNITED STATES PATENT OFFICE.

ALBERT T. REID, OF NEW YORK, N. Y.

TOILET CASE.

Application filed October 31, 1922. Serial No. 593,158.

To all whom it may concern:

Be it known that I, ALBERT T. REID, a citizen of the United States, residing at New York, in the county of New York and State of New York, have invented certain new and useful Improvements in Toilet Cases, of which the following is a specification.

The present invention relates to improvements in toilet cases, adapted for holding powder, rouge, or the like.

An important object of the invention is to provide a case of the above mentioned character, which is light, strong, durable, and compact in construction, whereby it is thin and may be carried in a hand bag or the like, with convenience.

A further object of the invention is to provide a reflector element or mirror, mounted between the casing sections, carrying the rouge or powder, and having means whereby the mirror may be adjusted for use with either casing section, or for use with both casing sections at the same time.

A further object of the invention is to provide a case of the above mentioned character, which is easy and convenient to operate.

A further object of the invention is to provide an economical refill for either casing section.

Other objects and advantages of the invention will be apparent during the course of the following description.

In the accompanying drawings forming a part of this specification, and in which like numerals are employed to designate like parts throughout the same,

Figure 1 is a side elevation of a case embodying my invention,

Figure 2 is a similar view, showing the casing sections and associated elements in open position,

Figure 3 is a face view of the device, showing one casing section open,

Figure 4 is a perspective view of the hinge embodied in the device,

Figure 5 is a plan view of one of the compact trays,

Figure 6 is a transverse section taken on line 6—6 of Figure 5,

Figure 7 is a fragmentary edge elevation

of the locking band, showing the pivoted opening of the same, and,

Figure 8 is a detail section through the hinged connection of the locking band and casing sections.

In the drawings, wherein for the purpose of illustration is shown a preferred embodiment of my invention, the numerals 1 and 2 designate casing sections, which are preferably cylindrical, having their inner sides open and their outer sides closed, as shown. These casing sections are preferably reinforced and stiffened by annular ribs or flanges 2'. The casing sections are preferably formed of metal, although any other suitable material may be employed.

The numeral 3 designates a hinge, as a whole, embodying leaves 4 and 5, which are secured, respectively, to the casing sections 1 and 2, by solder or any other suitable means. The leaves 4 and 5 carry spaced knuckles 6 and 7 respectively, which interfit, as shown, and are pivotally connected by means of a rod 8. This rod is preferably formed of resilient material and is extended at its ends beyond the knuckles 7, and bent into lateral spring arms 9, which engage within the sides of the casing sections 1 and 2 and are so tensioned that they automatically swing the casing sections 1 and 2, to the open position, when these casing sections are released.

The inner knuckles 6 are spaced, for the reception of a sleeve 10, having a headed stud 11 formed integral therewith. This sleeve 10 pivotally receives the rod 8.

The numeral 12 designates a preferably cylindrical locking band, preferably formed of metal, although any other suitable material may be employed. This band is of slightly smaller diameter than the casing sections 1 and 2, so that the casing sections may engage upon the opposite ends thereof, as shown. The locking band 12 is preferably provided with a reinforcing or stiffening rib 13, stamped outwardly therein, at its center. The rib or flange 13 serves as a stop for the edges of the casing sections 1 and 2, and also stiffens the locking band and associated elements.

As more clearly shown in Figure 7, the rib or flange 13 terminates at points 14, the side

- wall of the locking band 12 being flattened between these points, whereby the points 14 will clear the knuckles 7, when the locking band 12 is turned upon its pivot, as will be described. The flattened portion of the locking band 12 is provided centrally thereof with an opening 15, pivotally receiving the shank of the headed stud 11, whereby the locking band 12 has a swiveled connection 10 with the hinge 3. As shown in figure 2, the locking band 12 extends in the same direction of the casing sections 1 and 2, whereby the casing sections may be swung inwardly upon this locking band.
- 15 The numeral 16 designates a reflecting element or mirror, of any well known or preferred type, preferably in the form of a looking glass. This mirror has preferably one side only serving as a reflector. The mirror 20 is mounted within a preferably annular frame 17, mounted within the locking band 12. The frame 17 carries at diametrically opposite points, trunnions 18, which are pivoted within openings 19, formed in the 25 locking band 12, and preferably in the reinforcing rib 13. The frame 17 is disposed in spaced concentric relation within the locking band and is adapted to clear the head of the stud 11, when being swung upon its pivots 30 19.
- Arranged within the casing section 2 is a tray 20, having compartments 21 and 22 depressed therein. The compartment 21 is intended to hold a puff while the compartment 35 22 may hold a rouge compact. A compartment 23 is also pressed from the tray between the compartments 21 and 22 and is adapted to receive the usual lip stick. The numeral 24 designates lips, preferably 40 stamped from the material of the tray 20, and projecting over the compartment 23, and serving to normally hold the lip stick against displacement. These lips are preferably resilient.
- 45 A similar tray 25 is mounted within the casing section 1, and has compartments 26 and 27, depressed therein, for receiving a puff and powder compact. The trays are of course removable from the casing.
- 50 The casing sections 1 and 2 are locked to the locking band 12 by catches, preferably embodying recesses 27, to receive lugs 28. When the casing sections are slightly opened, the spring arms 9 will automatically throw 55 them to the open position.
- In the use of the device, the casing sections 1 and 2 may be opened and are preferably shifted to a more or less horizontal position. When this is done, the mirror 17 may 60 be turned upon its pivots 19 so that the mirror may be used with either casing section 1 or 2. When it is desired to use the mirror with both casing sections 1 and 2, as when it is desired to apply both powder and rouge to the face, the locking band 12 is turned
- upon its headed stud 11 until it assumes a position at right angles to or extending longitudinally of the casing sections 1 and 2. The mirror 16 may be suitably angularly adjusted within the locking band 12, if desired. 70
- It is obvious that a device has been produced which is convenient to operate, of simple construction, compact, and susceptible of a large range of adjustment, with the 75 operating parts permanently connected.
- It is to be understood that the form of my invention herewith shown and described is to be taken as a preferred example of the same, and that various changes in the size, 80 shape, and arrangement of parts may be resorted to without departing from the spirit of the invention or the scope of the subjoined claims.
- Having thus described my invention, I 85 claim:
1. A toilet case comprising, a pair of casing sections, a hinge for connecting the casing sections, a locking band to receive the casing sections thereon, and a reflecting element rotatably mounted within and carried by the locking band so that it may be used with either casing section. 90
2. A toilet case comprising, a pair of casing sections, a hinge for connecting the casing sections, a locking band arranged between the casing sections and adapted to receive the casing sections thereon, and a reflecting element angularly adjustably mounted upon the locking band. 95
3. A toilet case comprising, a pair of casing sections, a locking band arranged between the casing sections and adapted to receive the casing sections thereon, hinge means for connecting the casing sections and the locking band, and a reflecting element pivotally mounted upon the locking band, to be angularly adjusted with relation thereto. 100
4. A toilet case comprising, a pair of casing sections, a locking band arranged between the casing sections, and adapted to receive the casing sections thereon, hinge means for connecting the casing sections and the locking band, a reflector having one side only serving as a reflecting surface, and means for rotatably mounting the reflector within the locking band so that its reflecting surface may be used with either casing section. 110
5. A toilet case comprising, a pair of casing sections, hinge means connecting said casing sections, a locking band arranged between the casing sections and having a swiveled connection therewith so that the locking band may be shifted to a position longitudinally of the casing sections when they are in the open position, and a reflector angularly adjustably mounted within the locking band. 125

6. A toilet case comprising, a pair of casing sections, hinge means connecting said casing sections, a locking band arranged between the casing sections and having a swiveled connection therewith, and a reflector carried by the locking band.
7. A toilet case comprising, a pair of casing sections, a hinge embodying leaves secured to the casing sections and having 10 knuckles, a pivot element extending through the knuckles, a sleeve carried by the pivot element and having a pivot member, a locking band mounted between the casing sections and having an opening to receive the pivot member, and a reflector adjustably mounted within the locking band.
8. A toilet case comprising, a pair of casing sections, a hinge embodying leaves secured to the casing sections and having 20 knuckles, a pivot element extending through the knuckles, a sleeve mounted upon the pivot element between the knuckles and carrying a headed stud, a locking band arranged between the casing sections and having 25 an opening pivotally receiving the shank of the headed stud, and a reflector pivotally supported within the locking band.
9. A toilet case comprising, a pair of connected casing sections, a support carried by 30 the casing sections, and a reflecting element pivotally carried by the support so that it may be used with either casing section.
10. A toilet case comprising, a pair of coacting casing sections, a support connected 35 with one casing section, and a reflecting
- element pivotally carried by the support so that it may be used with either casing section.
11. In a toilet case, a pair of coacting casing sections, a hinge connecting the same, a 40 stud pivotally secured to the hinge, a support swiveled upon the stud, and a reflecting element carried by the support.
12. A toilet case comprising a pair of casing sections pivoted together for relative 45 swinging movement, a reflecting element provided with a single reflecting face, and means connecting the reflecting element with one casing section in a manner to permit of the said reflecting face of the element being 50 arranged remote from either casing section and in an upper position with respect to the other casing section, said reflecting element being enclosed by the casing sections when 55 they are closed.
13. A toilet case comprising, a pair of connected casing sections adapted to have relative opening movement, a reflecting element adapted to be enclosed by the casing sections when they are in the closed position, 60 and means whereby the reflecting element may be supported in either casing section with the same face thereof in the outer position with respect to such casing section, when the casing section is in the open position.

In testimony whereof I affix my signature.

ALBERT T. REID.
